TACK PULLER

Frank J. Braga, Hudson, Mass.

Application November 26, 1947, Serial No. 788,277

4 Claims. (Cl. 12—16)

1

This invention pertains to shoe manufacture and more especially to a tack puller for use in removing pulling-over tacks.

In my Patent No. 2,316,045, dated April 6, 1943, I disclose a novel method of making shoes of the stitch-down type which involves the step of pulling-over the toe portion of the upper and the insertion of two tacks which are driven through the margin of the upper, one at each side of the toe, into the bottom of the last. Thereafter, an extension sole is secured to the last bottom and the margin of the upper, intervening between the tacks, is sewed to the extension sole. Before completing the sewing of the upper to the sole, the pulling-over tacks must be removed. However, since these tacks have been driven into the bottom of the last and are substantially perpendicular to the last bottom, and since the extension sole overhangs and usually contacts the tack heads, difficulty has been experienced in removing these tacks expeditiously and without danger of damage to the shoe upper.

The present invention has for its object the provision of an instrumentality whereby the tacks may be removed readily and with little danger of injury to the shoe upper. A further object is to provide a tack puller comprising a novel pulling claw and means for supporting the claw in stationary position. A further object is to provide a tack puller having a pulling claw which may be adjusted to various heights for the accommodation of the user. Other and further objects and advantages of the invention will be pointed out in the following more detailed description and by reference to the accompanying drawings wherein

Fig. 1 is a side elevation of the tack puller of the present invention, portions of the supporting stand being broken away;

Fig. 2 is a front elevation of the upper part of the tack puller of the present invention;

Fig. 3 is a section substantially on the line 3—3 of Fig. 1;

Fig. 4 is a plan view, to small scale, of a shoe comprising an upper and an extension sole and showing the location of the pulling-over tacks;

Fig. 5 is a vertical transverse section, to larger scale, through a shoe showing a portion of the tack-pulling claw in operative engagement with one of the tacks preparatory to the removal of the tack; and

Fig. 6 is a fragmentary rear elevation showing the lower end of the pulling claw to larger scale than in Fig. 2.

Referring to the drawings, the numeral 1 des-

2

ignates a base or stand, for instance a casting or forging, having a horizontal foot portion, designed to be secured to a bench or other suitable support, and the upright member 2 to which a vertically adjustable post 3 is attached by means of bolts 4. The upright 2 and/or the post 3 are of any suitable dimensions requisite to provide the desired rigidity and to dispose the pulling claw at the proper height for convenient use.

10 Thus, for example, the length of the upright may be approximately 12 inches and the post 9 inches, and these parts may be of a width of the order of 1½ inches and of a thickness of ½ inch, assuming that the stock is steel or material of 15 equivalent strength characteristics.

A block 5 is fixed to the upper part of the post 3, for example by welding or by screws. This block may be a casting or a piece of bar stock, and is of a transverse width approximating that 20 of the post 3. As illustrated, the block 5 is approximately 2 inches in front-to-rear dimensions at its top, the front face 6 of the block sloping downwardly and forwardly, making an angle of approximately 80° with the lower surface 7 of the block. A clamping plate 8 is associated with this sloping forward surface 6 of the block, the clamping plate being secured to the block by means of bolts 9 and having a downwardly directed central reinforce tongue 8a, here shown as 25 gradually tapering in thickness toward its lower end. As here illustrated, the block 5 is provided in its forward face with a recess or slot 10 which receives the shank of the pulling claw, the recess being of such depth that when the claw is placed in the recess and the bolts 9 are tightened, the claw is held rigidly in operative position. By loosening the bolts 9, the claw may be adjusted up and down or removed for repairs or replacement.

30 The claw consists of a length of bar stock, for example, a length of hardened tool steel, preferably of the order of ½ inch wide and ¾ inch thick. A convenient length for this bar is 5 inches, although the length may be varied within wide limits.

35 As here illustrated, each end of this bar is provided with a series of teeth 12 of generally triangular shape. Preferably the ends 13 of these teeth describe a circular arc of a radius, for example, of ½ inch with its center on the center line of the bar. The toothed end of the bar is also bent rearwardly, as shown in Fig. 1, to provide a smooth, forwardly convex face 14, which may have a curvature of the order of 1½ inch 40 radius. This rearwardly concave end portion of

the bar is preferably tapered so that the teeth are sharp at their ends. Preferably, although not necessarily, the edges of the teeth are beveled, as shown at 15, at the rear side of the claw.

While the claw is shown as provided with teeth at its opposite ends, this is a matter of convenience since but one end of the claw is in use at the same time. By making the claw alike at its opposite ends, it is possible to reverse it when the teeth at one end have become dulled, thus saving material and the time of the user.

The claw is arranged substantially as shown in Fig. 1 with its toothed lower end spaced from the lower end of the reinforce tongue 8^a of the plate 8, this tongue providing a rigid front abutment for the claw to assist the latter in withstanding the stresses applied during use. As here illustrated, the tips of the teeth 12 are spaced approximately $\frac{3}{4}$ of an inch below the lower end of the reinforce tongue 8^a.

Fig. 4 illustrates, diagrammatically, a shoe in readiness for the removal of the pulling-over tacks. The upper U of the shoe has been assembled with the last L and its toe portion has been pulled over, for example, by the use of a commercial type of pulling-over machine, and two tacks T have been driven through the margin of the upper and into the bottom of the last. After the insertion of the pulling-over tacks, an extension sole S is secured to the bottom of the last, for example, by tacks, and, as here illustrated, the toe portion of the margin M of the upper intervening between the tacks T has been spread outwardly over the toe portion of the extension sole and has been permanently secured to the sole by a stitched seam Z. The upper is thus permanently fixed to the extension sole and it is now necessary to remove the tacks T before completing the union of the upper to the extension sole.

The mode of using the tack puller of the present invention for the purpose of removing these tacks T is illustrated in Fig. 5. Here the last is shown in transverse section. The margin of the upper U is lapped over the last bottom and the tacks T, which have been driven through the margin of the upper into the last bottom, are substantially concealed by the edge of the extension sole S. The heads of the tacks contact the extension sole so that the tacks are quite inaccessible and difficult to remove by any ordinary tack-pulling instruments.

Assuming that the shoe is in the condition shown in Fig. 5, the operator, holding the shoe by its opposite ends, lifts it so as to cause the lower end of the pulling claw to slide into the space between the upper and the extension sole and so that the teeth of the pulling claw engage the shank of the tack T. The operator then may pull the shoe bodily toward him, thereby to remove the tack but preferably rocks the lower part of the shoe toward him, using the curved surface 14 of the pulling claw as a fulcrum, the surface of the upper C, backed by the last L, rocking against the surface 14 and thus providing substantial leverage whereby the tack is readily drawn from the last. This operation is a matter of but a few seconds, and since the claw has the smooth, forwardly convex surface 14 it may be entered into the space between the upper and sole without danger of damaging the upper, the teeth of the claw being directed rearwardly so that they do not tend to stab into the upper material. By arranging the tips 13 of the teeth on an arc, the teeth are in the optimum position

for engaging the tack without requiring particular care on the part of the operator in holding the axis of the shoe exactly horizontal when he presents the shoe for engagement with the pulling claw.

While herein certain dimensions have been suggested as desirable, as these dimensions having been found from extended experiment to give the most desirable results, it is to be understood that the invention is not necessarily limited to these precise dimensions and that such modifications and rearrangements of parts and substitutions of materials as may be desirable under different conditions of use are to be regarded as falling within the scope of the invention as set forth in the following claims.

I claim:

1. In combination in a tack-pulling device for removing pulling-over tacks from a stitch-down shoe having a portion of its upper permanently united to an extension sole, a normally fixed pulling claw consisting of an elongate bar of tough, hard material terminating at its lower end in a series of teeth, the ends of the teeth describing a convex arc, said lower end of the bar being curved rearwardly to provide a smoothly rounded front face for contact with the shoe upper, and means rigidly but adjustably supporting the bar so that it inclines downwardly and forwardly at an angle of approximately 80° to the horizontal and with its toothed end spaced downwardly therefrom thereby to allow the toothed end to be entered between the shoe upper and the extension sole of the shoe.
2. In combination in a tack-pulling device for removing pulling-over tacks from a stitch-down shoe having a portion of its upper permanently united to an extension sole, a stand comprising a base designed to be attached to a fixed support, an upright carried by the base, a block fixed to the upright, said block having a front face which inclines downwardly at an angle of approximately 80° to the horizontal and which is provided with a claw-receiving channel, a clamping plate for securing a claw in the channel, and a claw consisting of a bar of hard, tough steel normally fixed in said channel with its lower end spaced below the block, the claw terminating at its lower end in a series of teeth whose tips are disposed in a downwardly convex arc, the lower part of the bar being curved and rearwardly concave.
3. In combination in a tack-pulling device for removing pulling-over tacks from a stitch-down shoe having a portion of its upper permanently united to an extension sole, a stand comprising a base designed to be attached to a fixed support, a vertically adjustable upright carried by the base, a block fixed to the upright, said block having a downwardly inclined front face provided with a claw-receiving channel, a clamping plate for securing a claw in the channel, and a claw consisting of a bar of hard, tough steel normally fixed in said channel with its lower end spaced below the block, the claw terminating at its lower end in a series of teeth whose tips are disposed in a downwardly convex arc, the lower part of the bar being curved and rearwardly concave, the clamping plate having a downwardly extending tongue designed to engage the front face of the claw thereby to support the latter in opposition to forward stress tending to bend the bar forwardly.
4. In combination, in a tack-pulling device for removing pulling-over tacks from a stitch-down

shoe having a portion of its upper permanently united to an extension sole, a stand comprising lower and upper, relatively adjustable parts, a claw-carrying block fixed to the upper of said parts, the front face of the block being inclined downwardly and forwardly at an angle of approximately 80° to the horizontal, a clamping plate, and means for drawing it toward the front face of the block, the block and plate defining a channel for the reception of a pulling claw, and a removable pulling claw normally fixed within said channel, said claw having tack-engaging teeth at its opposite ends.

FRANK J. BRAGA.
